UNITED STATES PATENT OFFICE

136,897

DESIGN FOR A HYDRAULIC PUMP

Marvin E. Wallis, San Mateo, Calif., assignor to
Brucon Company, San Francisco, Calif.

Application July 12, 1943, Serial No. 110,658

Term of patent 14 years

To all whom it may concern:

Be it known that I, Marvin E. Wallis, a citizen of the United States, residing in the city and county of San Mateo, and State of California, have invented new, original, and ornamental Design for a Hydraulic Pump, of which the following is a specification, reference being had to the accompanying drawing, forming part thereof.

Fig. 1 is a plan view of a hydraulic pump showing my new design.

Fig. 2 is a side elevational view of the hydraulic pump of Fig. 1.

I claim:

The ornamental design for a hydraulic pump, as shown.

MARVIN E. WALLIS.
